UNITED STATES PATENT OFFICE

ARTHUR MANNING, OF RUTHERFORD, NEW JERSEY

FUEL OIL TORCH

Application filed December 26, 1930. Serial No. 504,921.

This invention relates to a torch for various kinds of furnaces and the like, the general object of the invention being to provide means for introducing a mixture of fuel oil and steam into a mixing chamber into which is introduced a quantity of air so as to produce a highly combustible mixture, which when ignited in a furnace or the like will produce the minimum amount of carbon and soot and practically no smoke, the mixture burning with a blue flame and producing the maximum amount of heat.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is an elevation showing the invention in use.

Figure 2 is a vertical sectional view through the device, the view also showing part of the furnace in section.

Figure 3 is a section on line 3—3 of Figure 2.

Figure 4 is a view looking into the spray jet.

In these views, the numeral 1 indicates a cylinder passing through a wall A of a furnace or the like with its inner end provided with the inwardly extending fingers 3. This cylinder 1 forms a mixing chamber as will be hereinafter described. A cylinder 4 extends partly into the cylinder 1 and has its inner end closed by a cap 5 which is formed with the perforations 6. An elbow 7 is connected with the outer end of the cylinder 4 and is provided with a substantially spherical part 8 at the junction of its limbs and this elbow is connected with an air supply pipe 9 by a coupling 10. A pipe 11 extends through the top part of the spherical portion 8 of the elbow and has its lower end connected with the T 12 which in turn is connected with a pipe 13, the inner end of which extends through a centrally arranged hole in the cap 5. A spray

head is threaded to the inner end of the pipe 13 and is formed with the radiating baffles 15, the baffles and the shape of the interior walls of the head causing the steam and oil passing therefrom to be sprayed in the chamber 1. The head 14 is formed with an internal valve seat 16 for a needle valve 17 which has its shank or stem formed with a threaded part 18 which passes through a threaded hole in a spider 19 located in the tube 13 and said stem passes through the T 12, through a packing gland 20 in the T and said stem passes through a hole in the spherical part 8 and has a handle 21 at its outer end so that by rotating the stem by means of this handle the point of the valve can be moved toward or away from the valve seat.

A short pipe 22 is connected by the coupling 23 with the upper end of the pipe 11 and said pipe 22 is threaded in one end of a T-24 to which an oil pipe 25 is connected and a steam pipe 26 is also connected to the said T.

From the foregoing it will be seen that the steam and oil entering the pipes 22 and 11 will be mixed together and this mixture will pass through the pipe 13 into the spray head and be sprayed into the air in the chamber or cylinder 1, the air entering the chamber from the air supply through the elbow 7 and the cylinder 4 and through the perforations 6 in the cap 5 of the cylinder. The steam and oil leaving the head 14 will thoroughly mix with the air and thus cause a highly combustible mixture to be formed which will pass into the furnace or the like from the inner end of the cylinder 1, the fingers 3 of which act as baffles to increase the mixing action.

The flow of steam and oil can be instantly cut off by closing the needle valve and this also acts to regulate the amount of steam and oil entering the device. When it is desired to clean the device the valve in the oil line may be closed so that steam only will pass through the nozzle and the valve seat and this steam will thoroughly clean the parts in a short time. By providing the couplings shown the parts may be readily disassembled for repair and cleaning purposes.

It is thought from the foregoing descrip-

tion that the advantages and novel features of the invention will be readily apparent.

It is to be understood that changes may be made in the construction and in the combination and arrangement of the several parts provided that such changes fall within the scope of the appended claim.

Having thus described my invention, what I claim as new is:

A torch or hydrocarbon burner comprising:
10 a mixing cylinder having at its forward end an annular series of inwardly directed or deflected fingers, the said forward end of the cylinder being open and said fingers being grouped about the open end, and an oil and
15 steam conducting pipe extending into said cylinder toward the forward end thereof and disposed in the longitudinal center of the cylinder and spaced in rear of the forward open end thereof end equipped with a forward end
20 portion of bell mouth form and also equipped with radially disposed baffles in said forward portion.

In testimony whereof I affix my signature.

ARTHUR MANNING.
